(57) **CLAIM**

The ornamental design for a lid for a beverage container, as shown and described.

DESCRIPTION

FIG. 1 is a perspective view of a lid for a beverage container showing the novel design.

FIG. 2 is a front side view thereof.

FIG. 3 is a back side view thereof.

FIG. 4 is a left side view thereof.

FIG. 5 is a right side view thereof.

FIG. 6 is a top plan view thereof; and,

FIG. 7 is a bottom plan view thereof.

In each of the drawing figures, portions of the lid for a beverage container that are shown in broken lines depict environmental subject matter only and form no part of the claimed design.

1 Claim, 4 Drawing Sheets(56)
